[54] **PROCESS OF HIGHLIGHTING THE INDICIA ON A
WATCHBAND CALENDAR**
2 Claims, 2 Drawing Figs.

[52] U.S. Cl. **40/107,**
40/21, 40/137

ABSTRACT: A watchband calendar has the indicia thereof highlighted by spin-finishing the viewing surface to create sector patterns of reflected light by orienting the viewing surface to reflect light.

PATENTED SEP 7 1971

FIG. 1

FIG. 2

INVENTOR:

WALTER A. SCHOMBURG

alter, kress & whitford

ATT'YS

**PROCESS OF HIGHLIGHTING THE INDICIA ON A
WATCHBAND CALENDAR**

This is a continuation-in-part from a previously filed and copending application entitled WATCHBAND CALENDAR, Ser. No. 659,782 and filed July 31, 1967.

The invention is concerned with a quick reference calendar which is removably mounted upon the user's wristwatch band, as by folding sidewardly extending tangs into clinching relationship with the band. Such a device is necessarily small and oftentimes the calendar figures are difficult to discern. Through the use of a spin-finishing technique on the viewing surface, as well as orienting the viewing surface, not only is the surface esthetically enhanced but further, the viewability is improved significantly. The finishing of a device of this character, as well as orienting the same for purposes of highlighting the indicia, constitutes an important object of the invention.

The invention is described in conjunction with an illustrated embodiment in the accompanying drawing, in which:

FIG. 1 is an enlarged elevational view of the device prior to its installation on a watchband; and

FIG. 2 is a somewhat reduced scale perspective view of the inventive device as installed on a watchband, the watchband and associated watch being shown in fragmentary form.

In the illustration given, the numeral 10 designates generally the inventive device which is seen to be platelike body having a central portion 11 of generally rectangular configuration and integral sidewardly extending tangs or wings as at 12 and 13 which are adapted to be folded on themselves and underneath the watchband 14 (see FIG. 2) to form the configurations designated 12' and 13'.

The central portion is equipped with calendar indicia generally designated 15 which is seen to be the calendar for the month of Aug. 1967. It is contemplated that such devices will be available for each month throughout a given year and worn during that month. Devices of this general nature; i.e., central panels having the calendar indicia with laterally projecting foldable wings have been known.

The inventive contribution resides in providing the viewing surface of the device 10 with a spin-finish prior to imprinting and thereafter orienting the same with respect to light. The spin-finish is designated in the drawing by the numeral 16 and is seen to include a plurality of circular grooves concentrically related to the center 17 of the central panel 11. Also shown on the two views, are "highlighted" sectors as at 18, 19, 20 and 21, which create areas of increased discernibility, depending upon the position of the device 10 relative to incident light. In other words, by changing the location of the essentially planar viewing surface from that depicted in FIG. 1 to that seen in FIG. 2, the highlighted sectors are shifted from those designated 18 and 19 in FIG. 1 to those designated 20 and 21 in FIG. 2. Thus, the user merely by twisting the wrist slightly can highlight a given sector of the device for more readily ascertaining the date he is interested in.

In the production of the device, the platelike body is ad-

vantageously developed from bright aluminum sheet of the order of about 0.010 inches thick. Bright aluminum is a commercially available product and has at least one side burnished to a high sheen. It will be appreciated that the initial blank 5 may provide more than one of the inventive devices depending upon the manufacturing procedures utilized. The major dimension of the device is of the order of 1-1/2 inches and thus the blank should accommodate at least one such device and possibly a plurality. The blank is spin-finished, say with 10 the diameter of the outermost concentric circle being about 1-1/2 inches and this is achieved by rotating a resilient ended spinning shaft on the surface of the blank with the blank being lubricated by a grit material suspended in kerosene or oil. Once the spinning has been completed, the spun surface is 15 cleaned and then lithograph imprinted with the appropriate indicia. The ink is dried by baking and thereafter the imprinted side may be coated with a tinted, transparent lacquer or enamel which is also baked on.

It will also be appreciated that the concentricity of the various grooves making up the spin-finished surface yield slight depressions in the areas 22 and 23 which are in line generally with the folding lines employed to convert the planar wings or tangs 12 and 13 to the folded configurations 12' and 13', respectively, seen in FIG. 2.

25 While in the foregoing specification a detailed description of the invention has been set down for the purpose of illustration, many variations of the details herein given may be made by those skilled in the art without departing from the spirit and scope of the invention.

30 I claim:

1. A wristwatch calendar product made by the process of:
  - a. forming a spin finish on a thin sheet of bright metal by abrading said bright metal by rotating a resiliently ended spinning shaft against the surface of said metal while a grit material is positioned between the end of said shaft and said surface, whereby said abrasion forms a plurality of generally concentric score lines with a center point of scoring substantially coinciding with the axis of said spinning shaft,
  - b. forming said spin-finished sheet metal into a central panel with said center point of said score lines positioned at approximately the center of said panel, at least one tab being integrally formed on said central panel and dimensioned to at least partially wrap around a wristwatch band, and
  - c. imprinting a calendar on said panel with the center of said calendar being located at approximately said center point of said score lines,

whereby, when said watch calendar is mounted on a watch 50 strap, the normal wrist motion causes a variation in highlighting different areas of said panel and calendar.

2. The product made by the process of claim 1 and the added step of:
  - d. forming a transparent protective coating over the surface of said panel, score lines, and calendar.
